UNITED STATES PATENT OFFICE

2,622,420

DRINKING CUP

William W. Rice, Chicago, Ill.

Application July 7, 1949, Serial No. 103,447

1 Claim. (Cl. 65—13)

1

This invention relates to certain new and useful improvements in a drinking cup provided with one or more drinking nipples and an object of this invention is to provide a simple and improved arrangement for controlling the flow of fluid from the cup through either of the nipples.

Another object of the invention is to provide a drinking cup of the character hereinafter described which may be manufactured at an economical cost.

Another object of the invention is to provide a drinking cup especially adapted for use by infants, and one which is provided with a simple and improved arrangement permitting the infant to receive the fluid from the cup without danger of the infant's spilling the same or receiving an excessive amount. In this respect the cup is exceptionally useful during the teething period of the infant, this by reason of the fact that the infant can use the drinking or feeding nipple as a teething element.

Another object of the invention is the provision of a cup of this character which will be especially useful to bedridden patients, the cup being provided with a simple and improved arrangement whereby the patient or attendant may control or regulate the flow of the fluid from the cup through the drinking nipple while the patient is at rest either in a sitting or lying position in the bed or chair.

Another and equally important object of the invention is the provision of a drinking cup of the character hereinafter described which comprises parts readily and easily removed for cleansing purposes.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the invention;

Fig. 2 is a sectional detail view taken substantially on line 2—2 of Fig. 3;

Fig. 3 is a plan view of the same;

Fig. 4 is a plan view similar to Fig. 3, but illustrating the regulator in position for removal;

Fig. 5 is a perspective view of the regulator employed in the invention; and

Fig. 6 is a sectional detail view taken substantially on line 6—6 of Fig. 5.

The several objects of my invention are ac-

2

complished by the preferred form of construction shown in the accompanying drawing. In these drawings the cup is indicated at 10. This cup may be formed of any suitable material. Such cup comprises a cup section 11 and a cover 12 telescopically arranged together as shown. This is accomplished by providing on the cover 12 a depending flange 13 which is adapted to snugly fit within the peripheral edge portion 14 of the cup section 11.

This cup section 11 is provided with one or more handles 15 of any approved shape or construction.

The cover provides a top wall 16 disposed in a plane below the wall 17.

Formed preferably as an integral part of the cover 12 is a drinking or feeding nipple 18. Such nipple provides an upwardly and outwardly inclined passage 19 through which the fluid from the cup section 10 may flow.

Opposite this nipple 18 and preferably likewise formed as an integral part of this cover 12 is a second drinking or feeding nipple 20. This second nipple 20 like the nipple 18 has an upwardly and outwardly extending passage 21 formed therein and like the passage 19 communicates with the cup section 11.

Formed in this nipple 20 and extending in a horizontal plane and at an angle with respect to the passage 21 is an opening 22. This opening 22 is adapted to be closed by a flexible valve 23 formed as an integral part of a regulator 24.

Such regulator 24 is in the form of an elongated rod and provides at its end opposite the valve 23 a knurled finger knob 25 to facilitate moving the rod longitudinally of its length as well as to rotate the same. Between the knob 25 and the enlarged shank 26, from which shank extends the valve 23, the regulator is of reduced diameter to provide an intermediate central portion 24' adapted for slidable movement through a guide opening 27 formed in a bridge bar 28. Entrance to the opening 27 in a vertical direction is had through a slot 29 formed in the bar 28. The central portion 24' is provided with oppositely disposed flat surfaces 30 which reduce the diameter of the central portion 24' between these flat surfaces to a size such that will permit that portion of the central portion 24' to be freely passed through the slot 29, thereby to remove the regulator from the cover 12. However, when the regulator is rotated relative to the bridge bar 28, to a position to dispose these flat surfaces in a horizontal plane, the regulator can only be

50 moved transversely of the bar 28 for purposes of

disposing the valve 23 into and from valve closing position with respect to the passage 21.

To limit the sliding movement of the regulator relative to the bar 28 in its movement to remove the valve 23 from valve closing position with respect to the opening 21, I provide on the central portion 24 a stop lug 31.

The valve 23 may have a counterbore 32 formed in its end portion to increase its flexibility thereby to effectively seal the passage 21 when the valve 23 is disposed in valve closing portion with respect to such passage.

When my improved drinking cup is used by a baby or infant the nipple 18 is employed for drinking or feeding purposes. The child will extract the contents from the cup by sucking the same through the nipple as it would do in the case if a nursing bottle were employed. However, in order to reduce the efforts of the child during drinking or feeding, the mother may adjust the regulator 24 relative to the bridge bar 28 to such position as will permit the flow of the fluid in such a manner as the mother deems best.

It is intended that the nipple 18 be formed of semi-hard rubber or such material as may be used for teething purposes.

When my improved cup is used by bedridden patients or by patients whose physical condition will not permit them to sit or stand upright while drinking, either nipple may be employed but preferably it is recommended that the nipple 20 be employed because the passage 21 is of a larger diameter than the passage 19 of the nipple 18. By the use of the regulator 24 the patient may regulate the flow of fluid from the cup in such volume as is most desirable for the patient.

On the other hand, the patient may close the passage 19 by pressing his finger over the outer end thereof and, when the valve 23 is moved from valve closing position with respect to the passage 21, control the flow of the fluid from the cup through the passage 21. This is accomplished by removing the finger from over the passage 19 to permit a steady flow of the fluid through the passage 21 in such volume as the patient may desire.

The usefulness and simplicity of the construction of my improved drinking cup is apparent from the foregoing.

While I have illustrated and described the pre-

ferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

A drinking cup comprising a cup section, a cover therefor having a reduced portion frictionally insertable in the open top of the cup section, nipples formed integral with said cover at opposite corresponding sides thereof, with each nipple projecting upwardly and outwardly from the side walls of said cover and each having a passage therethrough communicating with the cup section whereby the contents of the cup section may be drunk from either side of said cover, a second passage formed in one of said nipples and bisecting said first mentioned passage in said nipple, and a regulator carried by the top wall of said cover between said nipples and provided with slidale valve means adapted to project through said second passage into said first mentioned nipple passage to control passage therethrough.
